Primary Examiner—T. Chase Nelson*Assistant Examiner*—Karen Acker(74) *Attorney, Agent, or Firm*—The H.T. Than Law Group(57) **CLAIM**

The ornamental design for a utility lighter, as shown and described.

DESCRIPTION

FIG. 1 is a rear view of an ornamental design for a utility lighter according to the present invention;

FIG. 2 is a front view thereof;

FIG. 3 is a bottom view thereof;

FIG. 4 is a top plan view thereof;

FIG. 5 is a left side plan view thereof; and,

FIG. 6 is a perspective view thereof.

The portions shown in broken lines are included for the purpose of illustration and form no part of the claimed design.
